SHARP FREEZING UNIT

Filed April 24, 1930

UNITED STATES PATENT OFFICE

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN

SHARP FREEZING UNIT

Application filed April 24, 1930. Serial No. 446,909.

This invention relates to a sharp freezing unit and has to do particularly with an extremely simple, inexpensive and compact cooling unit having a sharp freezing chamber.

Efficient heat transfer as well as hold-over capacity has become a major problem in connection with refrigerating systems of the type used in connection with domestic refrigerating units. The present invention has to do with a cooling unit which is much less expensive than the general type now in use and which at the same time provides for maximum heat transfer as well as hold-over properties.

More specifically, the present invention has to do with the forming of the interior walls of the sharp freezing chamber, and also other walls, of cylindrical members, or cylindrical tubing as the case may be, so as to provide for relatively inexpensive construction and also to form the interior wall of the sharp freezing chamber in a novel manner so as to prevent collapsing. In other words, to provide a flat surface for the sharp freezing container the cylindrical inner walls of the unit must be deformed in part from their true cylindrical shape and I have provided a novel manner of accomplishing this change in shape while at the same time strengthening the inner shell against collapsing.

Other features of the invention reside in novel details of construction as will be more clearly brought out in the specification.

In the drawings:

Fig. 1 is a vertical sectional view illustrating one manner of carrying out the invention and showing in particular the shape of the inner shell and the arrangement of the surrounding shells for carrying the refrigerating medium and the hold-over medium.

Fig. 2 is a sectional view taken on line 2-2 of Fig. 1.

Fig. 3 is a sectional view similar to Fig. 1 but illustrating a modified form of the invention whereby flat surfaces are provided at both the top and bottom of the sharp freezing chamber.

Fig. 4 is a diagrammatic view illustrating

the general manner of positioning my novel cooling unit in the usual mechanical refrigerating system.

Fig. 5 is a diagrammatic view illustrating another way of forming the sharp freezing chamber wherein the inner wall and outer wall are formed from a single piece of sheet metal.

The entire cooling unit or lowside may be generally designated 1 and in its general form 60 consists of an outer shell 2, an intermediate shell 3, and an inner shell 4.

In the preferred simple form shown in Fig. 1 wherein the cooling unit is adapted to receive a single sharp freezing container, the inner shell 4 is preferably cylindrical with the exception of a bottom flat surface 5. Of course, the inner shell 4 could be provided with suitable grooves for receiving the sharp freezing container but with this arrangement the contacting surface between the container and the walls of the sharp freezing chamber would be quite limited. However, it will be obvious that by providing a flattened wall 5 that the entire sharp freezing container will 75 rest on this flat bottom wall with the result that the surface area of contact will be greatly enlarged which will in turn result in a more complete and rapid heat transfer.

The space between the inner shell 4 and 80 the intermediate shell 3 is preferably filled with a refrigerant 6 which may be either liquid or gas, as it will be obvious that the cooling unit is well adapted to either the flooded type or dry system of refrigeration. 85 The space between the intermediate shell 3 and the outer shell 2 is preferably filled with artificial stone 7. This stone may be formed of what is known as oxy-chloride cement or may be formed of any other similar materials 90 which provide relatively good conductivity as well as good hold-over properties.

This material 7 is preferably plastic when inserted between the shells 2 and 3 and is allowed to harden. By enclosing the end 95 walls with suitable caps 8, as best shown in Fig. 2, it will be obvious that the stone lining 7 will be completely sealed with the result that a relatively cheap and even a relatively porous stone can be used with good results.

The outer shell 3 being cylindrical in form and reinforced by the stone lining 7 will obviously withstand any pressures created by the expanding or evaporating refrigerant. However, the inner shell 4 being formed by providing a flat bottom wall 4 would obviously tend to collapse very easily from the pressure exerted by the refrigerant. To overcome this I preferably form the inner shell so as to provide downwardly extending legs or flanges 9 and 10. These flanges may, if desired, be provided with outwardly extending portions 11 so as to permit of better contact with the walls 3.

By welding the legs 9 and 10 together, as best shown in Fig. 1, and by welding the flanges 11 to the intermediate wall 3, it will be obvious that the bottom wall 5 is materially strengthened against any strains which might be caused by the pressure of the refrigerant. This structure will also assist in correctly positioning the sharp freezing chamber formed by the walls 4 and 5.

A modified form of the invention is disclosed in Fig. 3 wherein the portion forming the actual sharp freezing chambers is formed in two halves which may be generally designated 12 and 13. These halves may be provided with flange members 9 and 10 similar to the structure shown in Fig. 1 and the upper portion of the chamber or chambers formed by the halves is so fabricated as to provide a flat wall 14 similar to the wall 5. Suitable flange members 15 are provided at the upper part of the unit formed by the halves 13 and 14 and these flange members may be welded together and secured to the intermediate wall 3 in the manner shown. By having a flat surface 14 at the top as well as at the bottom, it will be obvious that the sharp freezing containers will be in closer contact with the walls of the sharp freezing chamber whereby to effect a much quicker heat transfer and subsequent freezing of the ice cubes or other material.

In Fig. 5 I have illustrated a further modified manner of forming the interior shell 4 and the intermediate shell 3. In this case the two shells are preferably formed from one sheet of metal joined together at the point 16.

It will thus be seen that I have provided an extremely inexpensive, easily assembled, and compact cooling unit. The walls of the sharp freezing chamber or chambers are so fabricated as to best conform with the shape of the sharp freezing container or containers whereby to effect a rapid transfer of heat. The cooling medium is positioned immediately adjacent the wall of the sharp freezing chamber whereby to insure and maintain a relatively low temperature. The cooling medium is immediately surrounded by a large mass of stone which, while it acts as a good conductor whereby to effect transfer of heat units be-

tween the cooling medium and the interior of the space to be cooled, at the same time acts as an efficient hold-over whereby to maintain a given temperature for a relatively long time. This will permit the use of a relatively small amount of refrigerant in the cooling unit and will also permit of the maintaining of a higher temperature in the surrounding atmosphere.

What I claim is:

1. A cooling unit for refrigerating systems formed of three shells, the inner shell being open and adapted to receive a member to be cooled, a body of refrigerant around said inner shell and confined by the second shell, a mass of stone surrounding said second shell, and means forming a part of said inner shell and connected to the second shell for reinforcing the inner shell against collapsing. 75

2. A cooling unit for refrigerating systems formed of three shells, the inner shell being open and adapted to receive a member to be cooled, a body of refrigerant around said inner shell and confined by the second shell, a mass of stone surrounding said second shell, and confined by a third shell, and means forming a part of said inner shell and connected to the second shell for reinforcing the inner shell against collapsing. 80

3. A cooling unit for refrigerating systems formed of three shells, the inner shell being open and adapted to receive a member to be cooled, a body of refrigerant around said inner shell and confined by the second shell, a mass of stone surrounding said second shell, and means connected to said inner shell and to said second shell for positioning the inner shell within the second shell. 100

4. A cooling unit for refrigerating systems, comprising in combination an inner substantially cylindrical shell, a flat bottom formed in said shell for receiving a sharp freezing container and providing relatively great surface contact therebetween, a substantially cylindrical shell surrounding said first shell, and means connecting said flat bottom with said outer shell whereby to reinforce said flat bottom, and a mass of refrigerant confined between said two shells. 110

5. A cooling unit for refrigerating systems, comprising in combination an inner substantially cylindrical shell, a flat bottom formed in said shell for receiving a sharp freezing container and providing relatively great surface contact therebetween, a substantially cylindrical shell surrounding said first shell, and means connecting said flat bottom with said outer shell whereby to reinforce said flat bottom and position said inner shell centrally of the outer shell, and a mass of refrigerant confined between said two shells. 115

6. A cooling unit for refrigerating systems comprising an inner shell formed with a substantially flat bottom portion, an intermedi- 130

ate shell spaced circumferentially around said inner shell, said inner shell terminating in two flanges welded together and in turn secured to said intermediate shell whereby to reinforce the inner shell and position the same within the intermediate shell, and a mass of stone plastically applied around the intermediate shell and allowed to harden.

7. A cooling unit for refrigerating systems comprising a pair of spaced shells adapted to receive a refrigerant, said inner shell having a portion of the surface thereof flattened and reinforced against collapsing, said reinforcing portion being connected to said outer shell, and a mass of material surrounding the outer shell, said material having relatively good heat conducting and "hold-over" properties.

In testimony whereof I affix my signature.
